UNITED STATES PATENT OFFICE.

C. A. KELLOGG, OF ELYRIA, OHIO.

IMPROVED BED-BOTTOM.

Specification forming part of Letters Patent No. **56,570**, dated July 24, 1866.

To all whom it may concern:

Be it known that I, C. A. KELLOGG, of Elyria, in the county of Lorain and State of Ohio, have invented new and useful Improvements in Bed-Bottom Springs; and I do hereby declare that the following is a full and complete description of the construction and operation of the same, reference being had to the accompanying drawings, making a part of this specification, in which—

Figure 1 is a top view, and Fig. 2 is a side view, showing the same parts in another position.

A represents the side rail of a bedstead, and B represents the end of a slat. The rail is grooved, as shown at C, for the purpose of receiving the staple D. The staple is secured in the groove C by means of a pin, E, as shown in Fig. 2. The ends of the slats B are notched upon both sides, as shown in Fig. 2.

F represents a piece of elastic belting, about two inches wide and about four inches in length. It passes through the slot or open-

ing in the staple D, as shown in Figs. 1 and 2, and the ends are pressed into the notches, both upon the under and upper sides of the slat B, as shown at a a', and there secured by the wire gripe G, as shown in the drawings.

The angle or corners formed in the end of the slat B prevent the elastic belt F from drawing out. Each end of each slat forming the bed-bottom is constructed and mounted as herein described, the whole forming the bed-bottom, and there being no contact of either wood or metal, the bedstead will not squeak when in use; and besides, it forms a very easy and elastic support for the bed.

What I claim as my invention, and desire to secure by Letters Patent, is—

The staple D, pin E, and belt or strap F, in combination with the gripe G and slat B, as and for the purpose substantially as set forth.

C. A. KELLOGG.
